UNITED STATES PATENT OFFICE.

JOHN A. HAMILTON, OF MUNHALL, PENNSYLVANIA.

SHIPPING-CASE FOR COIN.

No. 861,277.

Specification of Letters Patent.

Patented July 30, 1907.

Application filed October 10, 1906. Serial No. 338,247.

To all whom it may concern:

Be it known that I, JOHN A. HAMILTON, of Munhall, Allegheny county, Pennsylvania, have invented a new and useful Shipping-Case for Coin, of which the 5 following is a full, clear, and exact description, reference being had to the accompanying drawings, forming part of this specification, in which—

Figure 1 is a perspective view of a shipping case embodying my invention; Fig. 2 is a transverse section of the same; Fig. 3 is a top plan view with the leather case removed and the top cover broken away; Fig. 4 is a longitudinal section on the line IV—IV of Fig. 3; Fig. 5 is a perspective view of a modified form of tray; and Fig. 6 is a detail view showing another 15 modification in the tray construction.

My invention has relation to cases for the transportation of coin, and is designed to provide a convenient and safe means for this purpose which shall be sufficiently strong to withstand the rough treatment received in transportation, and in which means are provided for the shipment of definite amounts of coin of different denominations.

With these objects in view, my invention consists in the novel construction and arrangement, and combination of parts, all substantially as hereinafter described and pointed out in the appended claims.

More specifically, my invention consists in a series of interchangeable trays adapted each to receive a series of coin-holding tubes, and which are placed or 30 stacked one above another upon a body or base portion, which also forms a tray, and which carries end portions within which the other trays are fitted and stacked, the whole being surrounded by a leather casing provided with suitable handles and locking 35 means.

In the drawings, the numeral 2 designates the base member of the case, which is formed with a series of concave seats or depressions 3 designed to receive and support a series of coin-containing tubes 4, (shown in 40 dotted lines in Fig. 2), said tubes extending longitudinally of the case from one end to the other. The member 2 is provided with the upwardly extending end portions 5, which constitute the ends of the case, the sides thereof being open and formed by the sides 45 of the coin trays. 6 indicates these trays, of which three are shown, the lower one resting upon the base member 2, and the others being stacked thereon one above another between the end portions 5. Each of these trays is formed at each end with a series of tube- 50 supporting seats 7 for the reception of coin tubes, and said trays may also be provided with a transverse supporting member 8, which is also provided with similar seats for the intermediate portions of the tubes. Each tray is preferably formed at each end with a central 55 vertical projection 9 which fits in a vertical groove or

guide-way 10 in the end portions 5, whereby the trays are secured against lateral movement.

The several trays may be duplicates of each other where the entire shipment of coin is of the same denomination, but where the shipment is made up of coin 60 of different denominations, the different trays are, as shown in the drawings, adapted to receive respectively coin tubes of different lengths and diameters. As seen in Figs. 2 and 4, this requires the arrangement of the end supporting seats 7 to be made at different distances 65 from the ends of the several trays in order to accommodate tubes of different lengths. For instance, a tray arranged to contain a definite shipment of twenty dollar gold pieces requires the use of tubes which are of larger diameter but shorter than the tubes which would 70 be used for a shipment of five dollar gold pieces. This also necessitates that, as shown in Figs. 2 and 4, some of the trays be arranged to seat the tubes transversely therein instead of longitudinally. Thus, the upper tray shown is provided with seats 7' at its sides to receive a series of transversely extending tubes. In all cases, the exterior dimensions of the trays is the same, so that they may be used interchangeably in building 75 up the case according to the character of the particular shipment of coin to be made. These trays are preferably constructed of metal or of paper fiber or wood suitably reinforced, and are of sufficient strength to stand rough usage in shipment. It will be seen, however, that they are protected from endwise thrusts by the inclosing end portions 5, and that the end projections 9 also receive the strains of side thrusts. These 80 projections 9 may, if desired, be of the dove-tail form shown at 9' in Fig. 6, the groove or guide-way 10' which receives them being of corresponding shape.

In some cases it may be desired to use the case for 90 shipping coin in bags, in which case an open tray 11 of the form shown in Fig. 5 may be employed. This tray may be the depth of the three movable trays, or of the depth of two of them, and of the same longitudinal and transverse dimensions, so that it will readily fit upon 95 the base portion 2 between the ends 5. The bags of coin are placed loosely within this tray.

12 designates the inclosing leather casing having side bottom and end portions which completely surround the built-up case, an interposing packing 13 of felt or 100 other suitable material being preferably employed. After the trays have been built up a top board or cover 14 is placed over them, and the closing flaps 15 of the casing 12 are brought down upon this cover. These flaps are provided at their free edges with the metal or 105 stiffening pieces 16, which fit one over the other when the flaps are folded down, said pieces being securely riveted through the flaps. The corner portions of the casing are preferably provided with reinforcements 17. 18 designate handle straps which are firmly riveted to 110

the casing, and which are provided with the tongues and buckles 19. These straps carry the handle loops 20, the loop at one side passing through openings 21 in the tongue ends of the straps, and the handle at the other 5 side passing through similar openings in the buckle-carrying ends of the straps, the straps being split and riveted as shown at 22 to permit the handles to be passed therethrough. This arrangement is one of great strength, inasmuch as when the case is lifted it will be 10 seen that the two handles pull against and brace each other.

Projecting upwardly at each end of the case are metal straps 23, which extend up through openings in the top plate or cover 14, and are formed with eyes 24 to receive 15 pad-locks 25, which are connected by a chain 26, which is preferably looped around the handle straps as indicated in Fig. 1. Said straps are also preferably provided with holes 23^a to receive a seating wire and seat.

Any suitable form of coin tube may be used in the 20 trays.

Various changes may be made in the details of construction and arrangement of the several parts without departing from the spirit and scope of my invention, since

25 What I claim is:—

1. A shipping case for coins, consisting of a rigid casing having closed ends, open sides and top, and a base portion forming a tray, and also a support for other trays, and a flexible casing surrounding and inclosing the rigid casing 30 and trays, and having opening flaps at the top; substantially as described.

2. A shipping case for coins, consisting of an inner structure having closed ends, open sides and top, and a base portion, a series of trays arranged to be superimposed upon said base, said trays being of the same exterior dimensions, but having differently arranged supports there-in whereby the different trays are adapted to receive coin tubes of different lengths and diameters, and a flexible casing surrounding and inclosing the inner structure and trays; substantially as described. 35

3. A shipping case for coins, consisting of a rigid inner structure having closed ends, open sides and top, and a base portion forming a tray, other trays arranged to be superimposed upon the base tray, and a leather casing inclosing the inner structure and having overlapping closing 40 flaps at the tops provided with locking means and with handles; substantially as described. 45

4. A shipping case for coin having an inclosing leather casing provided with closing flaps and with securing straps, and having tongue portions at one end and buckles 50 at the opposite ends, said straps also having handle loops, the loops at one side passing through the tongue portions of the straps and those at the opposite sides passing through the buckle-carrying portions of the straps; substantially as described. 55

5. In a shipping case for coin, a base member having open sides and rigid, closed ends, a series of removable trays arranged to seat one upon another and upon the base member, and having a sliding interfitting engagement at their ends with the said closed ends, and an outer 60 casing inclosing the whole and having means for securing the same; substantially as described.

In testimony whereof, I have hereunto set my hand.

JOHN A. HAMILTON.
